RIVETED CONSTRUCTION

John A. Larkin, New York, N. Y.

Application June 9, 1943, Serial No. 490,144

5 Claims. (Cl. 189—36)

This invention relates to a fabrication of parts constituting structural steel elements which may be used advantageously in building construction or framework.

The invention contemplates the integrating of various parts, components or pieces to produce an integer or structural integrality which will be of increased strength. Among others, it is contemplated to produce main columns in accordance with the invention. Such main columns because of the increased strength and structural characteristics, enable the erection of buildings to a greater height than heretofore possible with adequate safety factors being provided with regard to wind stresses, gravity load and legal requirements.

The invention also resides in the means by which the components or pieces are joined, united or secured.

The nature of the invention and its distinguishing features and advantages will appear when the following specification is read in connection with the accompanying drawing, in which—

Fig. 1 is sectional perspective of a portion of a column built up in accordance with the invention.

Fig. 2 is an enlarged fragmentary section of the column shown in Fig. 1, showing fasteners or rivets completely formed and the material for another prior to its formation.

Fig. 3 is a transverse section of a rolled column reinforced in accordance with the invention.

Fig. 4 is a modification of the reinforcement of a rolled column, a portion of which is shown.

Fig. 5 is a fragmentary section showing a further modification.

Fig. 6 is a view of a rivet blank.

Fig. 7 is a section showing the riveting of two relatively thin plates.

Heretofore it has been the standard practice in connecting, fastening or securing plates and the like to drill holes of equal diameter from end to end and insert therein a red hot rivet blank whose projecting end is pressed, hammered or swaged into a button or other head or countersunk formation. The aforesaid method wherein button or other heads are formed, fractures the fibre of the metal immediately under the heads so formed and so rendering the rivet of no definite value.

In accordance with the present invention, the capacity of the rivet grip is increased by gradually increasing the diameter or width of drilled and reamed rivet holes in opposite directions beginning at the intermediate contact point of the

components to be connected to each other. These rivet holes are in fact machine finished. Such increase from the intermediate point may be in the range of plus 5% to 10% greater diameter at the outer surface than the diameter at the intermediate contact point of each component. In this manner the rivet or fastener conforming to the rivet holes provides two resistance portions in the entire length thereof, and thereby eliminates the aforesaid fracturing of the molecular structure and so utilizes the rivet or fastener at maximum tension capacity. It follows therefore that it is possible to integrate various parts so that the integer will be of increased strength for the intended purposes.

It is to be understood that the taper of the rivets as shown in the several views of the drawing is shown in an exaggerated manner.

As shown in Figs. 1 and 2, by way of example, a built-up main column is provided. Use is made of a web plate 10, separate connecting angles 11, and separate flange plates 12. These components are fabricated or integrated as follows. The plate 10 is secured to the angles 11 by rivets 13. A single flange plate 12 is secured to two of the angles 11 by rivets 14 and two plates 12 are secured to the remaining two angles 11 by rivets 15.

In cases where an uneven number of members or components are secured to each other, the increased diameter or width of both the holes and the rivet blank will start from the inner surface of one of the outer members and will gradually increase toward the outer surface of said member. Thus in Figs. 1 and 2, for each rivet blank there is one conical hole in one related angle 11 to receive one conical portion of the rivet and the holes in the plate 10 and the other angle 11 are of gradually increasing diameter to receive the other conical portion of the rivet 13. It will therefore be seen one conical portion is longer than the other. In other words, the conical portions are in continuation of each other and flare outwardly from an intermediate point which is coincident with the contacting faces of plate 10 and an angle 11. Each rivet blank consists of a piece of malleable metal in the form of a pin which may be of uniform diameter as shown in Fig. 2 and designated 16 or have one preformed conical portion as shown in Fig. 6 in which said conical portion is designated 17. The rivet blank is made red hot and one end is bucked up while the other end is pressed, hammered or swaged to form one or two conical portions as the case may be. In this manner the plate 10 and angles

11 are riveted to each other and each of two of the angles 11 are likewise riveted to two of the plates 12.

In cases where an even number of members or components are secured to each other the conical portions of the rivet are equal and the holes conform thereto. Thus the rivets 14 have equal conical portions.

In the reinforced construction shown in Figs. 3 and 4, wherein a rolled I column 18 is reinforced by plates 19, there are two plates 19 secured to the flanges at one side of the column and three plates 19 secured to the other flanges thereof. Since the two plates and a flange consist of three members, the rivets 20 each have conical portions of unequal length, whereas the rivets 21 which connect four members, namely, three plates and a flange, have conical portions of equal length. Reinforcing the rolled column gives added strength thereto over that of the largest columns hitherto rolled by steel plants. Hence, the built-up columns, as well as the reinforced columns, make it possible to erect buildings to a greater height than heretofore with adequate safety factors regarding wind stresses, gravity load and legal requirements being anticipated.

In Fig. 4 a reinforcement involving the use of four plates 19 in connection with the flanges of a rolled column is shown. Hence, the rivets 22 are like the rivets 21 whose conical portions are of unequal length. In this case three of the plates are held by the longer conical portion while the shorter conical portion joins the remaining plate to the flange of the column.

In Fig. 5, as in other case where three members are used, the longer conical portion of the rivet 23 connects two of the members against separating movement away from the third member, which latter receives the shorter conical member.

In Fig. 7 relatively thin plates 24 are riveted to each other. In the case of thin plates where only shallow holes are possible, a rivet 25 is swaged to provide conical portions in conjunction with blocks 26 as well as the plates. The holes in each block 26 and the contiguous plate provide a conical wall to which the swaged metal conforms. The conical portions of the formed rivet are equal due to the use of an even num-

ber of members in accordance with the invention.

I claim:

1. A fabrication for building construction consisting of a plurality of plates laid flatwise against each other, and a plurality of fasteners extending transversely through said plates to secure the latter to each other and thus form a structural integrality, each of said fasteners consisting of a piece of malleable metal swaged to provide portions in continuation of each other and which flare outwardly from an intermediate point of the fastener, the diameter at the outer surface of the flare being not more than ten percent or less than five percent in increased diameter than the diameter at said intermediate point, said plates having machine finished holes therein to conform to the fastener.

2. A fabrication as set forth in claim 1, wherein said fastener portions may be of equal or unequal length.

3. A fabrication as set forth in claim 1, wherein said intermediate point occurs coincidental with the plane of the contacting surfaces of certain of said plates.

25 4. A rolled steel flanged column, and reinforcing means riveted to the flanges of said column, said means consisting of plates, and rivets engaging said plates and flanges, each of said rivets being of gradually increased diameter in opposite directions from an intermediate point with respect to the longitudinal axis of the rivet, said diameter at the outer surface being in the range of plus five to ten percent greater than the diameter at said intermediate point, and said flanges and plates having machine finished holes therein to conform to the shape of the rivets as aforesaid.

30 5. A structural integrality comprising a plurality of structural members and rivets securing said members to each other, said members having drilled and reamed holes therein gradually increasing in diameter in opposite directions from an intermediate contacting plane of certain members for each rivet, and each rivet conforming to the walls of said holes, said diameter at the outer surface being in the range of plus five to ten percent greater than the diameter at said intermediate point.

JOHN A. LARKIN.
